UNITED STATES PATENT OFFICE.

BENJAMIN F. BELLows, OF CLEVELAND, OHIO, ASSIGNOR TO THE ELECTRIC COMPOSITOR COMPANY, OF CLEVELAND, OHIO, A CORPORATION OF WEST VIRGINIA.

MACHINE FOR JUSTIFYING TYPE-LINES.

SPECIFICATION forming part of Letters Patent No. 727,267, dated May 5, 1903.

Application filed January 24, 1900. Renewed November 14, 1902. Serial No. 131,392. (No model.)

To all whom it may concern:

Be it known that I, BENJAMIN F. BELLows, a citizen of the United States, residing at Cleveland, in the county of Cuyahoga and State of Ohio, have invented a certain new and useful Improvement in Machines for Justifying Type-Lines, of which the following is a full, clear, and exact description, reference being had to the accompanying drawings.

10 The object of my invention is to introduce at proper points in an assembled line of type or matrices the proper number of spacers of the proper size to justify said line. The spacers employed to effect the justification are alike in so far as their construction is material to the present invention, except that they vary in thickness, wherefore all references herein to the size of the spacers has reference solely to their thickness.

20 The invention is equally adapted for use with matrix-assembling machines and with type-setting machines. The term "type" will, however, throughout this specification be used generically to designate the small blocks of metal which are assembled to make up the line to be justified whether these metal blocks have cameo or intaglio characters.

25 Before describing in detail the machine in which my invention is embodied I will state in general terms the principle and mode of operation of said mechanism. As the type are assembled one by one in line, said line is moved along distances equal to each addition to the line, the mechanism employed for this purpose being common to the assembling-machine and to the justifying mechanism. This movement of the line causes the movement of mechanism by which the aggregate width of the type assembled, or, in other words, the 30 length of the assembling line of type, is measured. Instead of introducing spacers into the line at the points where spacers are necessary—as, for example, between the words—tubes are introduced. The upper ends of 35 these tubes are severally in communication with a like number of spacer-magazines. Each magazine is divided into a plurality of magazine-channels in which are stored spacers of various sizes, each channel, how-

ever, containing only one size. Each of these 50 magazine-channels has an escapement which when operated releases one spacer only. This spacer falls into the tube associated with the magazine of which said channel is a part and through said tube is delivered into the type-line. The escapement-operating devices are arranged over a selecting-plate which carries a plurality of combinations of escapement-operating devices, preferably vertical pins, some of which, depending upon the position 60 of the plate, are adapted to engage with and operate some of the escapement-operating devices. The surface of this plate is divided in one direction into as many divisions as there are escapements, and each of these divisions is subdivided into as many equally-spaced rows as there are tubes. The plate is also subdivided in a relatively transverse direction into a plurality of equally-spaced rows, and these pins are placed at the intersections of these relatively transverse rows. This plate is capable of moving horizontally under said escapement-operating devices in two directions and is so moved as follows, to wit: It is moved a definite distance transversely of said devices, which are preferably 70 levers, whenever a tube is added to the line, and this movement of the plate determines the number of spacers which shall be released, and it is moved forward in the direction of the length of the levers a distance proportionate to the size of each type added to the line after the line has reached a justifiable length, and this movement of the plate determines the size of the spacers to be released, but does not vary the number. These pins are arranged empirically upon the plate in a plurality of combinations in such manner that whenever the plate stops after it has been moved in said two directions as many 75 pins thereon as there are tubes in the line will be in operative relationship with a corresponding number of escapement-levers which are associated with those magazines with which the tubes in the line communicate, and 80 the particular escapement-levers with which said pins are in operative relationship will when operated release spacers whose aggre-

gate size will equal the distance which the type-line is short of its desired length. When therefore the selecting-plate after it has received the two movements referred to is moved upward, these several escapement-levers will be operated, and as a result one spacer will fall through each tube in the type-line and will be left in said line when the tubes are withdrawn, and these spacers will be of the proper size to exactly justify the line. The power for moving the several parts concerned in the justification of the line is in the machine as shown derived from electromagnets which are connected in normally open circuits. In most cases these circuits are closed automatically and in proper sequence, and they remain closed long enough for the magnets to perform the work allotted to them, and then the circuits are automatically broken. It is not my intention, however, to limit the primary invention to combinations in which electromagnets are employed to move all or any of the movable parts, because it is obvious that other sources of power to move said parts may be employed if desired.

The invention consists in the construction and combination of parts shown in the drawings and hereinafter particularly described, and definitely pointed out in the claims.

In the drawings, Figure 1 is a front elevation of the mechanism embodying my invention. Fig. 2 is a right side elevation. Fig. 3 is a rear view of a part of the mechanism by which the introduction of additional types to the line is positively prevented when the line is as full as it can be to be justifiable. Fig. 4 is a plan view of the mechanism below the line 4 4 in Fig. 1. Fig. 5 is a front elevation of the mechanism shown and some mechanism which is not shown in Fig. 4. Fig. 6 is a rear view of the mechanism shown in Fig. 5. Fig. 7 is a sectional side elevation on line 7 7 of Fig. 6. Fig. 8 is a front view of the main slides. Fig. 9 is a plan view of the main slide and the associated compensating slide. Fig. 10 is an inside view of the compensated slide turned upside down. Fig. 11 is a right end view of both slides and some mechanism associated therewith. Fig. 12 is a rear elevation of the justifying mechanism above that which is shown in Fig. 5. Fig. 13 is a left end view of the mechanism shown in Fig. 12. Fig. 14 is a vertical sectional view, full size, showing one of the escapement-operating mechanisms, the selecting-plate, and wedges associated therewith. Fig. 15 is a horizontal sectional view of the governor shown at the bottom of Fig. 12. Fig. 16 is a right end view of certain mechanism just above the bed-plate 250. Fig. 17 is a left end view of the same mechanism. Fig. 18 is a plan view of the selecting-plate. Fig. 19 is a rear view of said plate, partly in section. Fig. 20 is a bottom plan view of the same, and Fig. 21 is a diagram-

matical view of the magnets and their connections.

I will now proceed with the specific description of the machine shown in the drawings, in which my invention is embodied, and attention is invited to the claims, which define what parts and combinations of parts of the mechanism so described are of my present invention.

The spacers 9 are stored in readiness for use in the magazines 1, 2, 3, 4, 5, 6, and 7, the lower ends of which converge and form contracted necks. A glass plate 10 (see Fig. 13) may form the front of all the magazines. Into the lower end of each neck the upper end of one of the assembling-tubes 23 projects. The lower ends of said tubes are supported on a horizontal plane surface 41. Seven magazines and seven tubes are employed in the machine as shown; but this number is empirical and less or more may be used, if desired. Each magazine is subdivided into a plurality of vertical spacer-channels 8. The several channels in any magazine contain spacers of different sizes. In the machine as shown fifteen different sizes of spacers are employed, the smallest being .04 of an inch in thickness, and they increase in thickness by .01 of an inch, the largest being .18 of an inch thick. The first magazine contains fifteen channels, and each channel contains a stock of spacers which differ from the other spacers in thickness. The second and third magazines contain ten channels each, and consequently only ten varieties of spacers. The magazines 4, 5, 6, and 7 contain, respectively, seven, six, five, and three channels and a corresponding variety of spacers. These numbers are all empirical and arbitrary and may be varied at will. Each spacer-channel has an independent escapement. In the form shown each escapement includes a lever 12, which is pivoted to the rear plate 11 of the magazines, and it has two prongs 13 and 14, which project through said rear plate 11 of the magazine-channel. Under normal conditions the lower prong 13 projects beneath the lowest spacer and supports the entire column of spacers in that channel. At the same time the other prong 14 does not project into the channel, but is at a position behind but just below the second spacer in the channel, and when the lever is rocked it moves beneath the second spacer and temporarily supports it. The tail 15 of this lever, which normally rests upon a transverse fixed bar 16, acts by gravity to hold the lever in the described normal position. A release-lever 17 is pivoted on a horizontal rod 20 to the rear plate of the magazine-channels. Its upper end enters a notch 19 in the lever 12 above its pivot, and the tail 18 of this lever normally lies in a substantially horizontal position, resting upon a fixed bar 21. On the under side of this arm is a downward-extending vertical pin 22, against which

specifically the lifting force is applied, whereby to rock this lever and through it lever 12, whereby the lowest spacer only is released from the channel. As will be seen from Fig. 12, these rearwardly-extending escapement-levers are arranged in a row at equal distances apart crosswise of the machine.

30 represents a selecting-plate which rests in a horizontal position upon a suitable supporting-frame 32 below the row of lever-arms 18. This frame is pivoted on the same axis with said lever 17—viz., the rod 20. Projecting upward from this plate 30 are a very large number of small vertical pins 31. This plate is capable of moving endwise—that is, transversely—of the machine and also forward and backward and during its movements toward its selecting positions moves to the left and forward, as indicated by arrows in Fig. 18.

20 By these two movements a large number of combinations of these pins may be brought directly beneath the operating-pins 22. Every time a tube is added to the line this plate moves a definite distance to the left 25 transversely of the machine, this distance being in the machine as organized .025 of an inch. Since there are seven tubes, this plate may move in the direction referred to .175 of an inch by seven equal steps. To understand the arrangement of the pins 31 upon this selecting-plate attention is called particularly to Fig. 18. This plate is divided crosswise of the machine into as many equal divisions .175 of an inch wide as there are 30 spacer-channels 8 and corresponding escapements—in the present case fifty-six. Each of these divisions is subdivided into seven (corresponding with the number of tubes) smaller spaces or rows (.025 of an inch wide) extending from the front to the back of the plate, and the pins 31 are placed empirically in some of these rows. It will be understood that all of the pins in the various rows of the first division of this plate are provided for operating 40 the escapement of the first spacer-channel under certain conditions to be described. All of the pins in the various rows of the second division of this plate are adapted to operate the escapement of the second spacer-channel, 45 and so on. Fig. 18 shows diagrammatically the subdivision of the plate referred to. Beneath the various divisions of this selecting-plate, as shown in Fig. 18, will be found decimal figures which indicate the thickness in 50 fractions of an inch of the spacers stored in the spacer-channels with which the pins in said divisions are associated. It will be understood that the organizer of this machine arbitrarily determines what sizes of spacers 55 shall be used and in what magazine-channels the different sizes of spacers shall be stored and then empirically determines what spacers should be released under different circumstances to complete the length of the line and 60 that the pins are placed upon the plate in the positions to effect the release of the proper spacers. As before stated, this plate is not

only capable of moving crosswise of the machine, but it is also capable of moving forward and backward. The machine as organized 70 is capable of supplying spacers when seven tubes are in the line which will lengthen the line .7 of an inch and when one tube only is in the line .04 of an inch, and it is capable under conditions which will arise in practice 75 of filling up any possible shortage in the line measured in one-hundredths of an inch between the two figures named—to wit, .04 and .7 of an inch—provided a sufficient number of tubes are in the line. In other words, 80 there are sixty-seven possible differences in the length of the line to be justified between the extremes named, and provision is made for practically justifying any of these short lines. It is also possible to space a line which 85 is not long enough to justify. The selecting-plate is therefore subdivided at right angles to the subdivisions first referred to into sixty-eight equal spaces or rows, each being, as shown, .025 of an inch in width. The 90 pins 31 are placed at the intersection of these relatively transverse rows—viz., those running forward and backward and those running crosswise of the machine. In the operation of the machine as soon as the type 95 which have been assembled fill all of the line except .7 of an inch this selecting-plate begins to move forward distances proportionate to the thickness of each addition of type to the line, and it will be remembered that for 100 each tube added to the line the plate moves to the left one step—in this machine .025 of an inch. Because of these two movements of the plate and the empirical arrangement of the pins thereon the plate will always be 105 in such position that those pins thereon which are directly beneath pins on the escapement-levers will release when the plate is moved up one space from each magazine whose tube is in the assembled line, and the aggregate 110 thickness of the spacers so released will be equal to the shortage in the line.

The type 9^a, which are to be assembled to form the line which the present invention is designed to justify, will preferably be stored 115 in suitable magazines. For the purposes of illustration the vertical channels 144 in Fig. 1 may be regarded as the magazines in which these types are stored, and some of these channels also contain spacers or quads, which 120 may be released whenever desired. Each magazine has an escapement-lever 145, which is operated by a vertically-movable release-rod 219, said rod being raised by a finger-key 211. (See Fig. 2.) The type are released one 125 by one, and they fall through a tube 146 onto a shelf 40, which is a part of the supporting-block 41^a. Just to the right at the lower end of this type-assembling tube is a plunger 43, which immediately the type falls upon the 130 shelf 40 pushes said type and all of the line which has been previously assembled a definite distance to the left upon said shelf. Any appropriate mechanism may be employed to

operate this plunger. The drawings show for this purpose an electromagnet 44, whose armature 45 is connected by a link 46 with one of the links of a toggle 47. This toggle when it is straightened out moves the plunger forward—that is to say, to the left—to push the type along, as stated. This magnet is connected in a normally open electric circuit. One end of the broken circuit is connected with a contact-finger 48, and the other end is electrically connected to a thin spring 42, which projects up through the shelf 40, directly beneath the type-assembling tube 146. The types fall, therefore, upon the spring 42, which is thereby forced downward into engagement with the contact-finger 48. This completes the circuit of the magnet 44, which thereupon attracts its armature. The toggle is thereby straightened out, and the plunger is moved forward, with the result of moving the type forward and off of this spring 42, which thereupon springs away from the contact-finger 48. This breaks the circuit of the magnet 44, whereupon the armature falls, flexing the toggle, and this causes the plunger 43 to return to its normal position in readiness to repeat the described operation every time a type is added to the line. When a tube 23 is pushed forward into the line, it strikes the rear edge of this spring 42 and pushes it forward into contact with the pin 49 on the contact-finger 48, thereby closing the circuit of the magnet 44. The result is that the plunger 43 operates as described, and the tube is thereby pushed to the left a distance equal to its width. Resting upon the same horizontal surface 41 upon which the tubes rest is a horizontal plate 50, which horizontal surface is behind, but a little above, the shelf 40, upon which the type-line is assembled. This plate 50 extends transversely across the machine substantially the entire width thereof. The forward edge of this plate is undercut, whereby it is raised above its support. In the under side of this raised portion are tongues and grooves 51, extending crosswise of the machine—that is to say, parallel with the assembling-shelf. This plate is connected by links 52 with arms 53, which are secured to a rock-shaft 54. By rocking this rock-shaft this plate may be moved bodily forward or backward, for purposes to be described. Normally it is in its forward position, as shown in Fig. 7.

55 A measuring-block 55 has a foot 56, which rests upon the same surface 41 upon which the plate 50 rests, and the measuring-block itself extends over the type-assembling shelf. On the upper side of this foot are tongues and grooves 57, which engage with the tongues and grooves 51 in the plate 50, whereby the block is guided in its movements. This block always occupies a position in advance of the line of type being assembled, and the first type in the line is in contact with it. This block is consequently pushed along by the type-line as the several type are added to

said line, and the distance between the face of this block and the rear face of the last type in the line is the length of said line.

70 A supplementary tube 24 forms the lower end of each spacer-assembling tube 23 and is pivoted thereto, whereby it may occupy an upright position even if the tube 23 is inclined. These supplemental tubes are open 75 on their front sides, and each has on its lower side a rearwardly-extended foot 25, in the upper surface of which are tongues and grooves 26, adapted to engage with the tongues and grooves 51 in the plate 50. When the 80 tubes are moved forward into line with the assembling type and the plunger 43 moves said tube to the left, the tongues and grooves in this foot engage with the tongues and grooves in said plate, and thereby said tube 8; is guided in its movement and held in the assembling type-line. The tube which is next to be forced into the line normally bears against the right end of the plate 50. It is moved forward into the line by an arm 62, 90 which bears against the rear edge of this foot, this arm being fast to the rock-shaft 60. When, therefore, the operator desires to introduce a tube into the line, this rock-shaft is caused to rock, and thereby said tube is 95 pushed into line, and the plunger 43 immediately pushes it to the left, its foot engaging with the tongues and grooves of plate 50. To cause this rock-shaft to rock with the results stated, the operator presses down on the space-key 70. This space-key in the construction shown engages with an arm 71 on one end of a pivoted ball-governor tube 72, thereby forcing down the raised end of said tube. A catch 73 on the vertical arm of a pivoted lever 74 projects through a slot 75 in the arm 71, and when the tube is depressed by the space-key this catch engages with the arm 71 and holds it down until a ball 76 in said tube rolls down to the then-depressed end thereof. 100 The ball strikes the projecting end of this catch 73, thereby disengaging it from the arm 71 of the governor-tube, which tube under the influence of a spring 77 resumes its normal position, and the ball-governor thereupon rolls back to its normal position therein. An electromagnet 80 has its armature 82 connected by a link 81 with an arm 61, attached to the rock-shaft 60. This magnet is connected in a normally open circuit, one 110 wire of which is connected with the insulated contact-spring 83. When the ball strikes the catch 73, it throws the end of the lever 74 up into contact with this contact-spring 83, and thereby the circuit of the magnet 80 is completed, because the spring 83 becomes thereby electrically connected with the metal of the machine. The magnet thereupon attracts its armature, whereby the rock-shaft 60 is operated, and the spacer-assembling tube is thereby pushed forward into the line, as described. 115 This governor-tube 72 is used so that there may be an interval of time after the space-key 70 is depressed before the spacer-tube

enters the line. This is necessary in order to give the type released from the type-magazines 144 just before the space-key was depressed time to fall through the long type-
5 assembling tube 146 onto the assembling shelf before the spacer-tube is inserted in the line. This is particularly necessary, because the lower end 147 of this type-assembling tube 146 is hinged at its upper end to the main
10 tubes 146, whereby its lower end may swing forward to a position in front of the type-assembling shelf 40, and, in fact, the lower end 147 of this tube is so pushed forward by each spacer-assembling tube when it enters the
15 line. When this spacer-tube 23 is forced to the left by the plunger 43, the type-assembling tube is swung back into the position to deliver the type onto the assembling-shelf. A horizontal arm 65, which is also fastened
20 to this rock-shaft 60, has a pawl 100 pivoted to its outer end. The upper end of this pawl is adapted to engage with ratchet-teeth 104 on the rear side of a vertically-movable plate 101. Every time this rock-shaft 60 is oper-
25 ated and a tube thereby inserted into the line this pawl is moved up the distance between two adjacent ratchet-teeth on this plate, and thereby lifts the plate. This plate is con-
30 nected by an arm 102 with the tail 103 of a vertically-movable stepped wedge 105, which is thereby moved up one step. This stepped wedge is located so that its stepped face may be engaged by a finger 37, which is secured to the selecting-plate 30. This selecting-plate
35 is under the influence of a spring 117, tending always to move it to the left, and thereby hold this finger in engagement with this stepped wedge. Everytime the stepped wedge is moved up when a tube is introduced into
40 the line this selecting-plate is permitted to move to the left a distance equal to the height of one of the steps of said wedge, and it is so moved by said spring, and said finger 37 then engages with the next step on said wedge 105.
45 The described mechanism is that through which the selecting-plate 30 is permitted to make one of its movements, hereinbefore referred to—that is to say, a movement in steps of .025 of an inch crosswise of the machine
50 when each tube is added to the line.

There are two slides in this machine—viz., the main slide 94 and the compensating slide 84. They move transversely of the machine in parallel paths which are also parallel with the path of the assembling type-line. The main slide is provided with a series of ratchet-teeth 95, the operative faces of which are one-fourth of an inch apart. The compensating slide has a pallet-lever 85 pivoted to it for engagement with said ratchet-teeth. The foot of the measuring-block 55, referred to, has in addition to the tongues and grooves on its upper face, before referred to, other tongues and grooves 58 on its lower face at
60 right angles to those first named, and these tongues and grooves engage with the co-operating tongues and grooves 93 in the upper

edge of a vertically-extended fin 96 on the main slide. It will be remembered that the block 55 is moved in advance of the assembling line which contains both matrices and tubes and that its total movement is always equal to the length of the line made up of spacers and tubes. By reason of the described connection between this block and the main 70 slide the latter necessarily moves an equal distance. The compensating slide, however, moves a distance which is only equal to the length of the line made up of type only—that is to say, it moves a distance less than the distance which the main slide moves equal to the combined thickness of all of the tubes in the line. These tubes are made one-fourth of an 8c inch in width, and, as before stated, the ratchet-teeth on the main slide have their 85 operative faces one-fourth of an inch apart. Every time the spacer-key is depressed the pallet-lever 85, referred to, is operated and the main slide is permitted to move forward one-fourth of an inch, because of the addition to 90 the line of the spacer-tube, but the compensating slide remains stationary. The mechanism for operating this pallet-lever is the following: An arm 63 of the same rock-shaft 60, which has been before referred to, is connected 95 by a link 64 with an arm 107, attached to another rock-shaft 108. This rock-shaft has two arms 109, between which extends a round bar 106, which is parallel to the rock-shaft. A lever 87 is pivoted to the compensating 100 slide, with a notch 88 in its end which receives this bar 106 and maintains its engagement therewith, regardless of the position in which the compensating slide may be. This lever 87 engages with the projecting tail of 105 the pallet-lever 85, and every time the rock-shaft 60 is moved this other rock-shaft 108 is likewise operated through the mechanism described, with the result of temporarily disconnecting the two slides 84 and 94 through the 110 operation of said pallet-lever. The main slide, therefore, moves forward, but the compensating slide remains stationary. These operations are repeated until the line is 115 long enough to be justified. This will be in 115 practice when the line contains all of the complete syllables of the copy which will go into it. When the line has reached the justifiable condition, it will be found that the compensating slide has been moved along 120 until an upwardly-extending arm 90 thereupon has come into contact with an adjustable stop 121 on horizontal bar 120, which is suspended by its ends from two freely-swinging links 122 and 123. A further movement 125 of the slide, due to the addition of more matrices, moves this bar and consequently causes these links to swing. One of these links has a nearly horizontal arm 124, to which is pivoted the lower end of the tail 126 of another 130 step-wedge 125, which by its position controls the forward movement of the selecting-plate referred to. Therefore this wedge is moved up after the arm 90 of the compensat-

ing slide has come into contact with this stop, and the movement is always proportionate to the width of the type added to the line. The operative or inclined face of this wedge has 5 sixty-eight equal steps which are .025 of an inch wide. The mechanism intermediate of said wedge and the bar 120 is so proportioned that for every .01 of an inch added to the line the wedge will be moved up the distance between two adjacent steps, and consequently the plate 30 will be permitted to move and will be moved forward .025 of an inch—viz., the width of each step—which is also the distance between two transverse rows of pins 10 thereon. When this plate 30 is in its normal position, before it has been permitted to move by reason of previous movements of either of said wedges the front transverse row of pins (the lower row, as shown in Fig. 18) is directly beneath the plane of the pins 22 on the escapement-levers. It, however, requires a movement of this plate one step to the left before any of the pins in said row come into proper operative relation with an 15 escapement-lever. When this plate has so moved one step to the left, (at the same time a tube is added to the line,) it will be seen by examining Fig. 18 that a pin 31, associated with the channel containing spacers .06 of an 20 inch in thickness in magazine 1, will be brought into operative relationship beneath the pin 22 on the escapement-lever associated with the said magazine-channel and that no other pin on the selecting-plate will be in operative 25 relation with any pin on the escapement-lever. By a second movement of this plate one step to the left another pin will be brought into operative position beneath the same escapement-lever. Another pin will also be 30 brought into operative relation beneath the pin on the escapement-lever of that spacer-channel in the second magazine which contains spacers .06 of an inch in thickness. By a third movement of this character pins 31 35 will be brought beneath these same escapement-levers and beneath the pin on the escapement-lever of the spacer-channel in the third magazine containing spacers of like thickness. This mode of action may continue until when seven spacers are in the line, although the plate 30 has not been moved forward at all, because the line is not of a justifiable length. The upward movement of this plate 30 will operate an escapement-lever associated with the channels containing spacers .06 of an inch thick in every one of the magazines. Because of this construction any short line which cannot be justified may nevertheless be spaced with spacers .06 of an inch 40 thick.

By an examination of Fig. 14 especially it will be seen that the stepped wedge 125 does not engage directly with the selecting-plate, but it does engage with the upturned edge of 45 a bar 38, which is rigidly, but adjustably, secured thereto. On the under side of this plate is a yoke 39, through which a shaft 110

passes, whereby the plate is held down upon the frame 32. This shaft is mounted in bearings on the under side of the frame 32. To the ends of this shaft two pinions 112 are fastened. One of these pinions is engaged by a gear-segment 113 on the upper end of an arm 114, which is attached to the rock-shaft 115. These two pinions engage with rack-teeth 29 75 on the under side of the plate 30. An arm 118 on this rock-shaft 115 is connected, by means of a link 119, with the armature 131 of an electromagnet 130. The spring 117 is connected at one end with a fixed pin 116 and 80 at the other end with a lever 127. One end of this lever is hooked into a slot in the link 119. The spring therefore exerts a continuous force, tending through the described mechanism to send plate 30 forward, thereby 85 holding the part 38 in contact with the wedge 125. The magnet 130 is connected in a normally open circuit; but when the circuit is closed the armature is moved with a force greater than the force of the spring 117, whereby the plate is moved through the mechanism described rearward to its normal position on frame 32. When it is so moved, the stepped wedge 125 falls by gravity to its normal position, and thus prevents the forward 90 movement of said plate under the influence of the spring 117 when the circuit of said magnet is again broken.

On the under side of the selecting-plate 30 near one end is a channel-bar 28. A friction-roller 136 upon the upper end of a lever 135 enters this channel-bar. An arm 137, which is rigidly attached to this lever, is connected, by means of a link 138, with the armature 139 of an electromagnet 140. The lever 127, before referred to, is pivoted to this link 138 at one end, while its other end enters a slot in the link 119. The same spring 117 which acts to rock the shaft 115 also acts through the described connections to rock 100 the lever 135 in such direction as will cause the finger 37 on the plate 30 to press against the stepped wedge 105. The magnet 140 is connected in a normally open circuit. When the circuit is closed, the armature is attracted 105 with a force superior to the force of the spring 117, whereby the lever 135 is moved in the opposite direction, with the result of returning the plate 30 to its normal position, whereupon the stepped wedge 105 falls by gravity 110 to the position shown in Fig. 12. When the circuit of the magnet 140 is broken, the spring 117 again exerts its force and through the described mechanism moves the plate 30, whereby the finger 37 will always bear against 115 the stepped face of this wedge.

In Figs. 13 and 14 a vertically-movable plain wedge 141 may be seen by the side of the stepped wedge. The inclined face of this plain wedge may be below the stepped face of the other wedge. A laterally-extended pin 142 on this plain wedge extends over the top edge of the stepped wedge. If through the action of the plunger 43, which

moves the line along, the compensating slide or the stepped wedge 125 acquire a momentum which carries them past the position in which they should stop, the selecting-plate, 5 if it were then allowed to come directly into contact with the teeth of the stepped wedge, would prevent the wedge from returning to its proper position. This action on the part of the selecting-plate is prevented by the 10 plain wedge referred to, because before the stepped wedge moves up far enough to come in contact with the pin 142 referred to its operative stepped face is above the plain edge of the other wedge 141, and therefore 15 the bar 38 on the selecting-plate can only move as far as the plain wedge will let it. It is not believed that the momentum of the parts will ever cause the plain wedge to be moved up too far. The selecting-plate being 20 engaged in its forward movement by the face of the plain wedge cannot prevent the stepped wedge from falling back into its proper position. When, therefore, all of the type have been added to the line which it should properly 25 contain, the first action of the mechanism is to draw the plain wedge upward and allow the selecting-plate to move forward into contact with the stepped wedge if it were not in contact with said wedge before.

30 It will be understood that this plain wedge is not a necessary part of the machine, but is only a precautionary element intended to act when necessary to prevent the selecting-plate from moving forward too far. It may be 35 that in practice this plain wedge will rarely, if ever, serve any useful function; but it is there prepared to serve a useful purpose, if necessary. The selecting-plate having been moved by the described mechanism and its 40 movement having been properly controlled by the two stepped wedges, the selecting-plate is in a position in which the proper number of pins thereon are in operative relationship with the escapements associated with 45 the spacer-channels of the several magazines which contain the proper size of spacers to accurately justify the line. The power which directly causes the upward movement of this selecting-plate is furnished by an electro- 50 magnet 150. A rod 149, connected with the armature 151 of this magnet, engages with the frame 32. The magnet is normally in an open circuit. When the circuit is closed, the armature is attracted, and this rod engaging 55 with the frame 32 swings it and the selecting-plate 30 upward upon the pivot 20, whereby the release-levers 17, which swing on the same axis, are operated and a spacer of the proper size is released and falls into each tube in the 60 line and through said tube into the line. It might be here noted that the upward movement of the frame 32 is limited by a shoulder 34 on an adjustably-fixed rod 35, which passes through a yoke 33 on the under side of this 65 frame. This yoke normally rests upon another shoulder 36 on the same rod. Following this action the spacer-tubes are drawn back-

ward out of the line and so, also, is the measuring-block 55. The slides are then drawn back to their normal position, whereby the 70 measuring-block 55, acting against the first tube, pushes all of the tubes back to their normal position, as previously described, in readiness to be again used.

As before stated, the power to cause the required movement of the described mechanism is furnished by electromagnets. These magnets are connected in normally open circuits. One pole of the electrical generator 179 is connected with one pole of each magnet. The other pole of the generator is connected with the metallic framework of the machine. When the other pole of any magnet is connected with the metallic framework, the circuit of the magnet is completed. The 80 means for completing the circuit of the electromagnet 44 and of the magnet 80 have been described. The other magnets (except 220) are intended to operate different parts of the mechanism, either simultaneously or in quick 85 succession, and therefore means are provided whereby the closing of the circuit of one magnet will automatically and after a proper interval of time close the circuit of another magnet, and so on until the cycle of operations which these magnets are designed to 90 produce is completed, and the several circuits of the magnets are again broken after the magnets have done their work.

After the line is set up and ready to be justified the line-key 178 is depressed. It contacts with a spring 177, which spring is electrically connected with one pole of the magnet 170. This completes the circuit of the magnet 170, because the line-key is electrically connected with the machine-frame. When this magnet attracts its armature 171, the line-key may be released, because the movement of said armature permits a spring 174 to move against an insulated contact-finger 173, which is connected in the circuit of said magnet. The armature has theretofore held the spring 174 out of contact with the finger 173. The spring 174 is electrically connected with a spring 176, which is normally in contact with the spring 175, this latter spring being electrically connected with the machine-frame. The circuit of the magnet 170 is thereby completed through a path which is wholly independent of the line-key. The movement 115 of the armature of this magnet produces two results: First, it rocks a lever 180, which is connected by a link 181 with said armature. This lever carries a spring-pawl 182, adapted to engage with a toothed extension 143 of the 120 plain wedge 141, whereby said wedge is lifted, so that it no longer prevents the direct contact of the selecting-plate bar 38 with the stepped wedge 125. Second, the same movement of this lever rocks a pivoted ball-governor tube 183, to which it is connected by a link 184, so as to change the inclination of 125 said tube. The ball 185 in said tube rolls to the other end thereof. When it reaches said

other end it strikes against the spring 175 and moves said spring out of contact with the finger 176, thus breaking the circuit of the magnet 170, whereupon its armature falls 5 and the ball-governor tube resumes its normal position. The ball rolling down to the opposite end of the said tube rolls over a thin spring 187, which is thereby depressed and forced against an insulated contact-piece 186, which is in the circuit of the magnet 150. The circuit of the magnet 150 is thereby completed, because the spring 187 is electrically connected with the frame of the machine. When the armature 151 of this magnet 15 moves, it causes the circuit of the magnet to be completed through another path, because it permits a spring 152 to come into contact with a finger 153, which is connected with one pole of the magnet. The spring 152 is 20 electrically connected with a spring 154, and a spring 155, which is normally in contact with the spring 154, is electrically connected with the frame of the machine. The upward movement of this armature 151 swings upward the frame 32, which carries the selecting-plate 30, and thereby the selected escapements are simultaneously operated and spacers are released into the assembling-tubes. The upward movement of this armature 25 also rocks a ball-governor tube 156, to which it is connected by a link 158. The ball 157 in this governor-tube rolls down to the depressed end thereof and strikes the spring 155, forcing it out of contact with the spring 154, and thereby the circuit of the magnet 150 is broken, its armature falls, and the governor resumes its normal position. The ball 157, rolling down toward the depressed end thereof, rolls over a thin spring 40 160 and forces it into contact with a contact-finger 161. This finger is connected electrically with the three magnets 130, 140, and 190, and since the spring 160 is electrically connected with the frame of the machine the circuits of these three magnets are completed. The circuits of the magnets 130 140 remain completed only so long as the ball holds this spring 160 down, but this is long enough for the magnets do their work. The magnet 140 45 attracts its armature and through the mechanism which has already been described rocks the lever 185 and draws the selecting-plate 30 crosswise of the machine to its starting-point. The stepped wedge 105 falls to its normal position, where it acts, as before explained, to prevent the movement of the selecting-plate in the opposite direction. The movement of the armature of the magnet 130 acts through the mechanism described to swing the arm 50 114, whereby the selecting-plate is moved rearward to its starting-place. The stepped wedge 125 therefore falls to its normal position, where it prevents the opposite movement of said selecting-plate, as described. 55 The armature 191 of the magnet 190 when it moves upward permits an insulated spring 193 to come into contact with a contact-fin-

ger 192, which is electrically connected with one pole of the magnet 190. The spring 193 is electrically connected with an insulated 70 spring 194, which normally is in contact with some part of the metallic frame—as, for example, the lug 195 on the rear part of the block, which supports the main and compensating slides and various other parts of the 75 machine. (See Fig. 6.) The circuit of this magnet is therefore completed through a path which does not include the spring 160, and therefore it remains completed when the ball 157 rolls off of said spring. The armature 80 191 is connected by a link 196 with an arm 59^a on the rock-shaft 54. When, therefore, the armature moves upward, this rock-shaft is rocked, and this movement of the rock-shaft, transmitted through the arms 53 and 85 52, draws the plate 50 rearward. This draws the tubes rearward out of the line, leaving the spacers in the line, and it also draws the measuring-block 55 rearward out of the line, although it remains operatively 90 connected with the slide 94. The slide 94 is then drawn to the left. This movement may be effected by drawing downward upon a cord 97, which is attached to the main slide and passes over a sheave 98. The main slide 95 94 engages with an arm 86 on the compensating slide, and this slide is also drawn backward, both slides reaching their initial or starting position. An insulated arm 99, which is attached to the compensating slide, engages 100 with the spring 194 when said slide reaches its initial position and moves the spring 194 out of contact with the lug referred to, and thus the circuit of the magnet 190 is broken. The backward movement of the main slide 105 110 draws back the measuring-block 55, which is, in effect, a part of said slide, and it pushes the spacer-tubes back to their normal positions at rest. When the circuit of the magnet 190 is broken, its armature falls, rock-shaft 54 reverses its movement, and the plate 115 50 moves forward, its right end serving as an abutment against which the spacer-tubes rest. This completes the cycle of operations, which result in justifying a line of type and of returning the mechanism to position in readiness to go through the same cycle of operations. The justifying mechanism, as shown, however, includes other mechanism not heretofore described which have important 120 functions to perform. For example, it is desirable and perhaps practically necessary to provide some means which will inform the operator when the line is nearly full and show him approximately how much more matter he can 125 add to the line. Before describing the means for this purpose attention is called to this fact—namely, that the more tubes there are in the line the shorter must be the type-line which can be justified. For example, if seven 130 tubes are in the line, room must be left for seven spacers. If the smallest spacers (.04 inch) are used, they will necessarily occupy .28 inch of space, whereas if only one tube is

in the line only one spacer will be required and that may possibly occupy only .04 inch. It will be necessary to bear these facts in mind in order to readily understand the mechanism to be now described.

A lever 205 is pivoted to the front side of the housing 204, in which the plate 101 is guided. To the lower end of this lever a bar 206 is pivoted, and this bar rests and slides upon an extension of the bar 120. On the side of the bar 206 an insulated contact-plate 207 is secured, and this plate is electrically connected with an electrically-operated signal, which may be an incandescent lamp 210. The other terminal of the lamp is connected with the generator 175. The lever 205 has a pin 208, which passes through an arc-shaped slot 203 in the housing 204 and into an inclined slot 101^a in the vertically-movable plate 101. As this plate is moved upward, as described, when tubes are introduced into the line the lever 205 will be swung to the right, and the contact-plate 207 will consequently be moved in the same direction. After the line has reached a justifiable condition the bar 120 begins to move to the left, and sooner or later (depending upon the position of the contact-plate 207, which, as stated, depends upon the number of tubes in the line) a finger 128 on bar 120 will strike this contact-plate, thereby completing the circuit of the lamp, which flashes the signal that the line is nearly as full as it should be to be justifiable. The actual space which may now be filled in with additional type is approximately indicated by the distance between this finger 128 and a contact-spring 212 on the lower end of a swinging lever 213. This lever is insulated from the machine, but is electrically connected with the magnet 220. The operator must see to it that this finger 128 shall not touch the contact-spring 212, because thereby the circuit of this magnet is completed. The function of this magnet is to lock the mechanism whereby the type are released, and it effects this result through the following mechanism: The escapements of the type-magazines are operated by vertically-movable release-rods 214, which are connected with finger-keys 211. A frame 216 is pivoted adjacent to the upper ends of these release-rods, and it has a cross-bar 217, which may be swung over the tops of all of said release-rods. The armature 221 of the magnet 220 is connected by a link 222 with an arm 218 of this frame. When, therefore, the circuit of the magnet 220 is completed, this frame will be swung on its pivot until the cross-bar 217 is over the tops of the release-rods 214, whereby the vertical movement of said rods is prevented, which of course prevents the operation of the escapements by which the type are released. This mechanism is called the "key-lock," and obviously it does not matter whether this frame engages with one part or another of the train of mechanism of which the type-releasing keys are com-

monly at one end and the type-escapements at the other. The lever 213 has its position varied to carry the contact-spring 212 toward the finger 128 through the contact with it of a friction-roller in the end of an arm 111, which is attached to the vertically-movable plate 101. It is obvious that the more tubes there are added to the line the farther will this lever be swung to the right, and consequently the sooner will this contact-spring 212 meet the finger 128. In other words, the more tubes there are in the line the shorter will be the actual type-line when the type-release mechanism becomes locked.

It will not infrequently happen that more than seven spacers are required in a line. The machine as organized is only adapted to deliver seven spacers through the tubes. If other spacers are introduced into the line, they must be in the form of plain quads and must be introduced by some other means than through the tubes. As is common in machines of this class, quad or plain spacers are stored in magazines like those which contain the type, and they are capable of being released by similar finger-keys. As shown in the drawings, 211 indicates a quad-key, and 219 a quad-release rod, which rod by its vertical movement operates the escapement of a quad-magazine which contains quads .06 inch wide. The operator may by depressing this quad-key release a quad and cause it to enter the line. The operator, however, becomes accustomed whenever a spacer is desired in the line to depressing the space-key 70, and therefore mechanism is provided in this machine whereby the depression of this space-key after seven tubes are in the line will have no other effect than to cause the operation of this quad-release rod, whereby a quad is added to the line.

By reference particularly to Figs. 16 and 17 a bar 162 is seen pivotally connected with the quad-release rod 219, and under normal conditions it hangs vertically downward from its support. It has a forwardly-extended arm 163, in which there is a vertical slot 164. The pin 165, which connects the link 64 with an arm 107, passes through this slot and through another slot 66 in the link 64. Until seven tubes are in the line this lever 162 is back out of the way of all moving parts; but after seven tubes have been introduced into the line the lever 162 is swung forward over a pivoted pawl 67 on the end of an arm 68, attached to the shaft 60.

Looking now at Figs. 8 and 9 particularly, a beveled lug 91 will be seen on the inner face of the main slide 94. If seven tubes are introduced in the line and comparatively few type, this main slide will have moved independently of the compensating slide such a distance that this lug will come into engagement with the tail 78 of the lever 87, and thereby this tail will be depressed. This, through the described intermediate mechanism, will cause the rock-shaft 108 to be rocked,

and this rocking action through the link 107 will draw the bar 162 forward and hold it forward during the assembling of the remaining portion of the line of type. When, now, 5 the space-key is depressed and by the action of the parts described the rock-shaft 60 is rocked, the pawl 67 on the end of the arm 68 on said rock-shaft engages beneath the lower end of this bar 162 and pushes it upward. 10 This pushes up the release-rod 219 and causes the release of a quad, which falls through the type-assembling tube into the line. It might be here stated that whenever this beveled lug 91 on the main slide comes into operative relation with the tail of the lever 87 the front end of the pallet-lever 85 is in engagement with a shoulder 89 on the end of the main slide 94, whereby the movement of said slide 94 is necessarily accompanied thereafter by 15 a corresponding movement of the compensating slide.

Having described my invention, I claim—

1. In a machine for justifying a type-line, a movable plate carrying a plurality of combinations of operating devices arranged in 25 relatively transverse intersecting rows, substantially as described, whereby the movements of said plate in one direction vary the number of the devices in the combination which are brought into operative positions, and the movements of the plate in a relatively transverse direction bring different combinations into operative positions but do not vary the number of devices in said combinations, substantially as specified.

2. In a machine for justifying a type-line, the combination of a selecting-plate carrying a plurality of pins placed in different combinations at the intersections of two series of 40 relatively transverse divisions of said plate, a plurality of spacer-holding channels, escapements for said channels, and means for moving said plate in two relatively transverse directions to bring the different combinations 45 of said pins into operative relationship with said escapements, and means for moving said pins against said escapements whereby to operate them, substantially as specified.

3. In a machine for justifying a type-line, 50 the combination of a plurality of spacer-holding channels, and their escapements, with a movable selecting-plate carrying a plurality of combinations of escapement-operating devices, and adapted by its movement in one direction to bring an increasing number of 55 said escapement-operating devices into operative relation with said escapements, and by its movement in the other direction to bring other combinations of said operating 60 device into operative relationship with the escapements of channels holding spacers of different sizes, substantially as specified.

4. In a machine for justifying a type-line, 6 the combination of a plate carrying a plurality of combinations of operating devices placed at the intersection of relative trans- 75 verse divisions of said plate, mechanism for

causing said plate to move, in one direction, as many equal steps as there are to be justifying-spacers in the line of type, and mechanism for causing said plate to move in a relatively transverse direction distances proportionate to each addition of type to the line after the line has reached a predetermined length, whereby the position of said plate determines both the number and the size of the spacers which must be added to the line to justify it, substantially as specified. 70

5. In a machine for justifying a type-line, the combination of a plurality of spacer-releasing escapements, and a movable selecting-plate which is under the influence of a force tending to move it in two relatively transverse directions, a stepped wedge which engages with said plate and opposes its movement in one direction, means for moving said wedge one step for each space needed in the line, a second stepped wedge which engages with said plate and opposes its movement in the other direction, and means for moving 80 said wedge, after the type-line has reached a predetermined length, distances proportionate to each addition to the line, and a plurality of escapement-operating devices carried by said plate and arranged thereon in 85 different combinations which are adapted, through the two movements of said plate, to be brought into operative relationship with various combinations of said escapements, 90 substantially as specified. 95

6. In a machine for justifying a type-line, the combination of a plurality of spacer-releasing escapements, and a movable selecting-plate which is under the influence of a force tending to move it in two relatively transverse 105 directions, a stepped wedge which engages with said plate and opposes its movement in one direction, means for moving said wedge one step for each space needed in the line, a second stepped wedge which engages with 110 said plate and opposes its movement in the other direction, and means for moving said wedge, after the type-line has reached a predetermined length, distances proportionate to each addition of type to the line, and a plurality of escapement-operating devices carried by said plate and arranged in different 115 combinations which are adapted through the two movements of said plate to be brought into operative relationship with some of said escapements, and mechanism for returning said plate to its initial position, substantially as specified. 120

7. In a machine for justifying a type-line, the combination of a plurality of spacer-releasing escapements, and a movable selecting-plate which is under the influence of a force tending to move it in two relatively transverse 125 directions, a stepped wedge which engages with said plate and opposes its movement in one direction, means for moving said wedge one step for each space needed in the line, a second stepped wedge which engages with said 130 plate and opposes its movement in the other

direction, means for moving said wedge, after the type-line has reached a predetermined length, distances proportionate to each addition of type to the line, and a plurality of escapement-operating devices carried by said plate and arranged thereon in different combinations which are adapted, through the two movements of said plate to be brought into operative relationship with some of said escapements, said plate having rack-teeth on its under side, a shaft, and pinions carried thereby engaging said rack-teeth, a gear-segment engaging one of said pinions, and means for operating said gear-segment whereby to move the plate in one direction in opposition to said force, substantially as specified.

8. In a machine for justifying a type-line, the combination of a plurality of spacer-releasing escapements, a movable plate which is under the influence of a force tending to move it in two relatively transverse directions, a stepped wedge which engages with said plate and opposes its movement in one direction, means for moving said wedge one step for each space needed in the line, a second stepped wedge which engages with said plate and opposes its movement in the other direction, means for moving said wedge, after the type-line has reached a predetermined length, distances proportionate to each addition of type to the line, and a plurality of escapement-operating devices carried by said plate and arranged in different combinations which are adapted through the two movements of said plate, to be brought into operative relationship with some of said escapements, a channel-bar secured to the under side of said plate, a swinging lever whose upper end enters the channel in said bar, means for operating said lever, substantially as specified.

9. In a machine for justifying type-lines, the combination of a plurality of spacer-holding channels and escapement-operating levers respectively associated with said channels and all pivoted on the same axis, a substantially horizontal frame pivoted upon the same axis, and means for swinging said frame upward upon its pivot, with a selecting-plate supported by said frame and carrying a plurality of combinations of escapement-operating devices arranged at the intersection of relatively transverse divisions of said plate, and means for moving said plate in one direction to bring a combination thereon containing the proper number of operating devices into operative relationship with said escapement-levers, and means for moving said plate in a relatively transverse direction to bring into operative relationship said escapement-levers escapement-operating devices associated with channels containing spacers of the proper size, substantially as specified.

10. In a machine for justifying a type-line, the combination of a plurality of magazines each having a contracted discharge-neck, and being divided into a plurality of channels

adapted to contain different varieties of spacers, an escapement associated with each channel, spacer-assembling tubes which are severally in communication with the discharge-necks of the several magazines, and means for simultaneously releasing one space from each of several magazines and from such channels in said magazines that the aggregate width of the spacers so released shall be equal to the shortage in the line of type to be justified, substantially as specified.

11. In a machine for justifying a type-line, the combination of a plurality of spacer-magazines each having a contracted discharge-neck, and being divided into a plurality of channels adapted to hold spacers of various sizes, an escapement for each channel, an assembling-tube in communication with the neck of each magazine, means for determining from what magazines and from what channels in said magazines spacers must be released to space and justify a line of type, and means for operating the escapements associated with the channels thus determined upon, substantially as specified.

12. In a machine for justifying a type-line, the combination of a plurality of spacer-holding channels and their escapements, a plurality of tubes which are severally in communication with a plurality of said channels, a space-key, and intermediate mechanism through which the lower ends of said tubes are introduced *seriatim*, in lieu of spacers, into an assembling line of type, a selecting-plate carrying a plurality of spacer-operating pins arranged in different combinations thereon, and means for moving said plate equal distances in one direction whenever a tube is introduced into the line, and mechanism for moving said plate in a relatively transverse direction distances proportionate to each addition of type to the line after said line has reached a predetermined length, and means for moving said plate toward said escapements to operate the selected combination of said escapements, substantially as specified.

13. In a machine for justifying a type-line, the combination of a plurality of spacer-holding channels and their escapements, a pivoted support below said escapements, and a plate movably mounted upon said support, said plate carrying a plurality of combinations of spacer-operating pins, means for moving said plate in equal steps in one direction, and means for moving said plate in a relatively transverse direction distances proportionate to each addition to the line after the line has reached a predetermined length whereby various combinations of pins are brought into relative relationship with said escapements, and means for swinging said support upon its pivot, substantially as specified.

14. In a machine for justifying a type-line, the combination of a plate, capable of moving in two relatively transverse directions, and carrying a plurality of combinations of

escapement-operating pins, a spring which exerts its force to move said plate in said two directions, a stepped wedge which engages with said plate to limit its movement 5 in one direction, a space-key and intermediate mechanism whereby the actuation of the space-key moves said stepped wedge the distance of one step substantially as specified.

15. In a machine for justifying a type-line, 10 the combination of a plurality of magazine-channels for holding spacers of various sizes, escapements for these several channels, and a plurality of spacer-assembling tubes, which are severally in communication with a plurality of said channels, and are adapted to have their lower ends introduced, in lieu of the spacers, into the type-line to be justified, 15 with a selecting-plate carrying a plurality of combinations of escapement-operating devices, means for moving said plate in one direction as many equal steps as there are tubes in the line, and means for moving said plate, in a relatively transverse direction, 20 distances proportionate to each addition of type to the line after said line has reached a predetermined length, whereby to bring the proper combination of escapement-operating devices on said plate into operative relation with the proper escapements, substantially 25 as specified.

30 16. In a machine for justifying a type-line, the combination of a plurality of magazine-channels for holding spacers of various sizes, escapements for these several channels, and a plurality of spacer-assembling tubes which are severally in communication with a plurality of said channels and are adapted to have their lower ends introduced, in lieu of the spacers, into the type-line to be justified, 35 with a selecting-plate carrying a plurality of combinations of escapement-operating devices, means for moving said plate in one direction as many equal steps as there are tubes in the line, and means for moving said plate 40 in a relatively transverse direction distances proportionate to each addition of type to the line after said line has reached a predetermined length whereby to bring the proper combination of escapement-operating devices 45 on said plate into operative relation with the proper escapements, and means for moving said combination of escapement-operating devices against said escapements, substantially 50 as specified.

55 17. In a machine for justifying a type-line, the combination of a plurality of spacer-magazines each having a contracted discharge-neck, and being subdivided into a plurality of channels adapted to hold different kinds 60 of spacers, an escapement for each channel, and a plurality of assembling-tubes which are severally in communication with the discharge-necks of the several magazines, and are adapted to have their lower ends introduced, in lieu of spacers, in a type-line, with 65 a plate carrying different combinations of devices adapted to engage with and operate said

escapements, mechanism for causing the movement of said plate in one direction as many equal steps as there are tubes in the 70 line, mechanism for causing said plate to move in a relatively transverse direction distances proportionate to the addition of type to said line after the line has reached a predetermined length, and means for moving said plate so as to cause the selected combination of escapements to be operated by the escapement-operating device on said plate which have been brought into operative relationship therewith, substantially as specified. 75

18. In a machine for justifying a type-line, the combination of a plurality of spacer-holding channels and their escapements, a selecting-plate carrying a plurality of combinations of escapement-operating pins, two levers and 80 intermediate mechanism between said levers and plate whereby said levers may move said plate in two relatively transverse directions, a spring and intermediate mechanism whereby said levers are subjected to a force tending to so move them, a plurality of tubes which are severally in communication with a plurality of said channels, means for introducing said tubes, in lieu of spacers, into an assembling line of type, a stepped wedge 85 which engages with said plate and opposes its movement in one direction, means whereby the wedge is moved one step contemporaneously with the insertion of each tube into the line, a second stepped wedge which engages with said plate and opposes its movement in the other direction, and means whereby it is moved, after the line has reached a predetermined length, distances proportionate to the width of each addition to the line, 90 substantially as specified.

19. In a machine for justifying a type-line, the combination of a plate capable of moving in two relatively transverse directions and carrying a plurality of combinations of 100 escapement-operating pins, a spring which exerts its force to move said plate, a stepped wedge which engages with said plate and opposes its movement in one direction, a plain wedge which engages with the same side of 105 said plate, means whereby the movement of the stepped wedge may cause a movement of said plain wedge, and mechanism whereby each addition to the line of type after it has reached a predetermined length causes a proportionate movement of said stepped wedge, 110 and means for drawing the said plain wedge out of engagement with the plate when the line is completed, substantially as specified.

20. In a machine for justifying a type-line, 115 the combination of a plurality of spacer-magazines having contracted discharge-necks and being subdivided into a plurality of channels adapted for holding spacers of different sizes, a plurality of assembling-tubes whose upper 120 ends are loosely inserted in the necks of said magazines, supplemental tubes pivoted to the lower ends of said tubes and resting upon a suitable support, means for moving said sup-

plemental tubes into the path of an assembling line of type, and means for releasing a spacer from a suitable channel in each magazine associated with the tubes which have 5 been so introduced into the line, substantially as specified.

21. In a machine for justifying a type-line, the combination of a plurality of spacer-magazines each divided into a plurality of channels adapted for containing spaces of various sizes, spacer-assembling tubes which are severally in communication with said magazines, which tubes are capable of having their lower ends moved forward and backward and to the right or left, and supplemental tubes pivotally connected with the lower ends of said assembling-tubes and having rearwardly-extended feet which feet are provided with tongues and grooves, with a plate capable of 20 moving forward and backward and having tongues and grooves for engagement with the tongues and grooves on the feet of said supplemental tubes, and mechanism for drawing said plate rearward whereby to withdraw all 25 of said tubes out of the line of type, substantially as specified.

22. In a machine for justifying a type-line, the combination of a plurality of spacer-magazines each divided into a plurality of channels adapted for containing spaces of various sizes, spacer-assembling tubes which are severally in communication with said magazines, which tubes are capable of having their lower ends moved forward and backward and to the right or left, supplemental tubes pivotally connected with the lower ends of said assembling-tubes and having rearwardly-extended feet which are transversely grooved, with a movable plate which lies just behind the assembling-shelf and has transverse tongues and grooves for engagement with the corresponding tongues and grooves in said feet, which plate acts normally to prevent said tubes from swinging to the left, means for 45 severally pushing the lower end of said tubes forward and then to the left whereby the tongues and grooves in their feet engage with the tongues and grooves in said plate, and means for drawing said plate rearward to withdraw 50 said tubes out of the line of the type, substantially as specified.

23. In a machine for justifying a type-line, the combination of a plurality of spacer-magazines each divided into a plurality of channels adapted for containing spaces of various sizes, spacer-assembling tubes which are severally in communication with said magazines, which tubes are capable of having their lower ends moved forward and backward and to the right or left, supplemental tubes pivotally connected with the lower ends of said assembling-tubes and having rearwardly-extended feet which feet are provided with tongues and grooves, with a plate capable of moving 65 forward and backward and having transverse tongues and grooves for engagement with the

corresponding parts of the feet of said supplemental tubes, a rock-shaft, mechanism connecting the rock-shaft and plate, an electromagnet, its armature, and connections between the armature and rock-shaft, and means for closing the circuit of said electromagnet, substantially as specified. 70

24. In a machine for justifying a type-line, the combination of an assembling-shelf, means for delivering type singly onto said shelf, two slides side by side and movable in paths substantially parallel to the assembling-shelf, a measuring-block operatively connected with one of said slides, and adapted to extend over the assembling-shelf in front of the assembling line of type, means for pushing each addition to the line to the left whereby the said block is moved a distance equal to the width of each addition, ratchet-teeth on one of said 85 slides, a pallet-lever on the other slide which engages with said ratchet-teeth, a plurality of spacer-holding magazines, assembling-tubes which are severally in communication with a plurality of said channels, mechanism for moving said tubes severally forward over the assembling-shelf, and mechanism for operating the pallet-lever every time a tube is so moved forward, substantially as specified. 90

25. In a machine for justifying a type-line, the combination of mechanism which is adapted to assemble type in a line and to introduce a spacer-assembling tube in lieu of spacer into said line, means for moving the line along distances equal to each addition to the line, 100 a measuring-block which occupies a position in front of the line and is consequently moved whenever the line is moved, a slide with which said measuring-block is operatively connected, a compensating slide movable by the side 105 of the first slide, and means whereby the slides are normally connected but are disconnected every time a tube is added to the line, whereby although the main slide moves a distance equal to the total length of the line the compensating slide moves only a distance equal to the length of the line made up of type only, with a movable wedge, mechanism adapted to be moved by said compensating slide whereby said wedge is moved upward distances proportionate to the addition of type to the line after the line has reached a predetermined length, and a selecting-plate whose movement in one direction is controlled by said wedge, substantially as specified. 110 115

26. In a machine for justifying a type-line, the combination of the main slide having equally-spaced ratchet-teeth, the compensating slide carrying the pallet-lever for engagement with said ratchet-teeth, a lever having 120 a notched end pivoted to the compensating slide adapted to engage with and to operate said pallet-lever, a rock-shaft, two arms secured thereto, a bar engaging in said notch and secured to the lower ends of said arms, 125 and means for rocking said rock-shaft, substantially as specified. 130

27. In a machine for justifying a type-line, the combination of a main slide carrying ratchet-teeth, a compensating slide carrying a pallet-lever, a lever for operating said pallet-lever also pivoted to said slide and having a notch in its end, with a rock-shaft, two arms secured thereto, a bar secured to said arms and entering said notch, a space-key and intermediate mechanism whereby the operation of the space-key rocks said rock-shaft, substantially as specified.

28. In a machine for justifying a type-line, the combination of a main slide carrying ratchet-teeth, a compensating slide carrying a pallet-lever, a lever for operating said pallet-lever also pivoted to said slide and having a notch in its end, with a rock-shaft, two arms secured thereto, a bar secured to said arms and entering said notch, an electromagnet connected in a normally open circuit, means whereby the operation of the space-key completes said circuit, and intermediate mechanism between the armature of said magnet and said rock-shaft, substantially as specified.

29. In a machine for justifying a type-line, the combination of the main slide having equally-spaced ratchet-teeth, the compensating slide carrying the pallet-lever for engagement with said ratchet-teeth, a lever having a notched end, which is pivoted to the compensating slide and is adapted to engage with and operate said pallet-lever, a bar engaging in said notch, two arms to which said bar is secured, and means for simultaneously rocking said arms, a beveled block on the main slide adapted to engage with the tail of the lever having the notched end when the slides have moved a certain distance relative to one another, substantially as specified.

30. In a machine for justifying a type-line, the combination of a compensating slide, and mechanism whereby it is moved a distance equal to the widths of all of the type which have been assembled in the line, two swinging links, a bar hung on the lower ends of said links and carrying an adjustable stop adapted to be engaged by said slide or some rigid connection therewith, an arm connected with one of said swinging links, a stepped wedge and connections between said arm and stepped wedge, substantially as specified.

31. In a machine for justifying a type-line, the combination of a longitudinally-movable bar and means whereby it is moved, after the line has reached a predetermined length, distances equal to each addition of type to said line, a bell-crank lever operated by the movement of said bar, a vertically-movable stepped wedge, and mechanism connecting said bell-crank lever and wedge, with a selecting-plate carrying a plurality of combinations of escapement-operating devices, and means for moving said plate against said stepped wedge, substantially as specified.

32. In a machine for justifying a type-line, the combination of a space-key, and a device

which is movable in one direction step by step every time the space-key is depressed, with another device, and means for moving it in the opposite direction distances proportionate to each addition of type to the line after the line has reached a predetermined length, electrical contact-pieces adapted to be brought into contact through the relative movement of said two devices, and an electrically-operated signal which will be closed when said two contact-pieces come together, substantially as specified.

33. In a machine for justifying a type-line, the combination of a plurality of channels for holding spacers of various sizes, a plurality of spacer-assembling tubes which are severally in communication with a plurality of said channels, means for introducing the lower end of said tubes, *seriatim*, in lieu of spaces, into a line of type, a longitudinally-movable bar, and mechanism whereby said bar will be moved, after the line has reached a predetermined length, distances proportionate to each addition of type to the line, an electrical contact-piece carried by said bar, a part movable in the opposite direction to that in which said bar moves, and mechanism whereby it is so moved, step by step, when spacer-tubes are inserted into the line, electrical contacts carried respectively by said bar and device which contacts are adapted to be brought together by the movement of said parts, and an electrically-operated signal connected in a normally open circuit which will be closed by the contact of said two contact-pieces, substantially as specified.

34. In a machine for justifying a type-line, the combination of a plurality of channels for holding spacers of different sizes, a plurality of assembling-tubes which are severally in communication with a plurality of said channels, and are capable of having their lower ends introduced *seriatim*, into an assembling line of type, a main slide, and mechanism whereby it is moved a distance equal to each addition to the line whether of type or tubes, a compensating slide normally connected with said main slide, and means for disconnecting them whenever a tube is added to the line, a space-key, an intermediate mechanism for introducing the tubes *seriatim* into the line, a stepped wedge, and mechanism whereby it is moved one step every time the space-key is operated, a longitudinally-movable bar carrying an adjustable stop, swinging links on which said bar is suspended, an arm on the compensating slide adapted to engage with said stop, an arm secured to one of said links, a stepped wedge, and mechanism connecting it with said arm, and a selecting-plate movable in two directions which plate engages with said two stepped wedges whereby its movements are respectively opposed, means for moving it always against said two stepped wedges, a plurality of combinations of escapement-operating devices carried by

said plate, and escapements capable of being operated by said devices, substantially as specified.

35. In a machine for justifying a type-line, 5 the combination of a stepped wedge adapted by its position to determine the number of spacers which shall be released, with a space-key, and means whereby each operation of said space-key moves said stepped wedge one 10 step, substantially as specified.

36. In a machine for justifying a type-line, the combination of a plurality of spacer-assembling tubes, a space-key, and mechanism whereby the actuation of the space-key causes

15 the tubes to be introduced, *seriatim*, in lieu of spaces, into the assembling type-line, with a quad-magazine, and mechanism for releasing the quads singly therefrom, and mechanism for automatically making an operative 20 connection between the quad-releasing mechanism and the mechanism set into action by the said space-key, after all of the tubes have been introduced into the line, substantially as specified.

25 37. In a machine for justifying a type-line, the combination of a plurality of spacer-assembling tubes, a space-key, and mechanism, which includes a rock-shaft, whereby the actuation of the space-key causes the tubes to 30 be introduced, *seriatim*, in lieu of the spacers, into the assembling line of type, a quad-magazine, and mechanism, which includes a vertically-movable release-rod, for releasing the quads singly from said magazine, a bar pivoted at its upper end to said release-rod, and

35 hanging in a substantially vertical position, an arm on said rock-shaft, and mechanism for automatically swinging said arm over said

rock-shaft arm when all of the tubes have been introduced into the line, substantially 40 as specified.

38. In a machine for justifying a type-line, the combination with the mechanism for releasing the type from their several magazines, of a device adapted to be moved into 45 locking position with respect to said mechanism, and means whereby when the type-line contains all of the type which it can hold and still remain justifiable, said locking mechanism is moved to the locking position, 50 substantially as specified.

39. In a machine for assembling and justifying lines of type, the combination of mechanism for measuring the length of the line of type, mechanism for counting the number of 55 spacers required in said line, mechanism for releasing the type, two contact-pieces which are moved toward each other respectively the one being moved equal distances whenever the space-key is operated, and the other 60 being moved after the type-line has reached a predetermined length, distances proportionate to each addition to the line, mechanism for locking the type-releasing mechanism, an electromagnet connected in a normally 65 open circuit which will be closed when said contact-pieces come into contact, and mechanism whereby the electromagnet will operate said locking mechanism, substantially as specified.

In testimony whereof I hereunto affix my signature in the presence of two witnesses.

BENJAMIN F. BELLOWS.
